UNITED STATES PATENT OFFICE.

FRANK ARTHUR SIMONDS, OF GRAND RAPIDS, MICHIGAN, ASSIGNOR TO SIMONDS HEATING AND SPECIALTY COMPANY, OF FREMONT, MICHIGAN, A CORPORATION OF MICHIGAN.

CONTROLLER FOR RADIATOR-VALVES.

No. 910,092.

Specification of Letters Patent.

Patented Jan. 19, 1909.

Application filed March 24, 1906. Serial No. 307,902.

To all whom it may concern:

Be it known that I, FRANK ARTHUR SIMONDS, a citizen of the United States, residing at Grand Rapids, in the county of Kent and State of Michigan, have invented certain new and useful Improvements in Controllers for Radiator-Valves; and I do hereby declare the following to be a full, clear, and exact description of the invention, 10 such as will enable others skilled in the art to which it appertains to make and use the same.

My invention relates to improvements in controllers for radiator valves, and its object is to provide improved means for automatically opening and closing said valve whenever there is a change of temperature in the apartment heated by the radiator to which the valve may be attached, to provide 20 a device adapted to displace a part of an ordinary globe valve, and co-act with the case thereof; and to provide the device with various new and useful features, hereinafter more fully described and particularly pointed out in the claims, and it consists essentially of a piston attached to the movable member of the valve and moving in a cylinder adapted to displace the gland of a globe valve and connected at its respective ends to 30 a vacuum line, and provided with means to alternately open and close the respective passages between the ends of the cylinder and said line; and means for admitting outer air to the end of the cylinder that is thus cut off from the vacuum line, said valves preferably being operated by a double solenoid, in turn operated by an electric circuit shifted from one coil to the other by a thermostat located in the apartment heated by the 40 radiator, as will more fully appear by reference to the accompanying drawings, in which:

Figure 1. is a side elevation of a device embodying my invention; Fig. 2. a horizontal section of the same on the line 2—2 of Fig. 1.; Fig. 3. a vertical section of the same on the line 3—3 of Figs. 1 and 2; Fig. 4. a vertical section of the same at right angles to Fig. 3 and on the line 4—4 of Fig. 2.; and Fig. 5. a reduced side elevation showing my device attached to a radiator.

Like numbers refer to like parts in all of the figures.

1 represents a cylinder for the operating 55 piston 8, and 2 a similar cylinder in line

therewith for the balancing piston 7. These cylinders are screw threaded at the lower end to fit in place of the gland of a globe valve, and connected by an axial opening 3 through which opening extends a rod 5 connected at its lower end to the valve 4 to be operated. In this rod is a passage 6 connecting the inlet side of the valve with the upper part of the lower cylinder 2, in which cylinder is a balancing piston 7 fixed on the 60 rod 5, by which arrangement the piston 7 balances the valve 4 by equalizing the pressure below the valve and above the piston. The valve is thus readily lifted from its seat or closed as occasion requires by the 70 piston 8.

To operate the valve, the piston 8 is attached to the upper end of the rod 5 and moves in the cylinder 1. This piston 8 is operated by the outer air entering at one 75 side, the vacuum at the other side of the piston leaving the air pressure unbalanced. To connect the cylinder 1 with the vacuum line of the system, a passage 9 extends from the lower end of the cylinder to a chamber 10 in the cylinder head and a passage 11 through the cylinder head connects the upper end of the cylinder and a chamber 12 in said head. Between these chambers 10 and 12 is a chamber 13, which latter is connected to the vacuum line 33 by means of a pipe 17. This vacuum line is exhausted by any convenient means, and is preferably connected to the discharge side of the radiators, as shown in Fig. 5, and with a steam 90 trap 32 interposed therebetween, but a separate vacuum line may be provided, if preferred.

Between the chamber 13 and the respective chambers 10 and 12 are openings alternately closed by opposing valves 14 and 15 mounted on a longitudinally movable rod 16 slidable in openings in the axes of the plugs 18 and 19 in the outer ends of the chambers 10 and 12. These valves are fixed on this rod and so spaced apart that as one valve seats and closes the opening, the other valve is moved away from the seat and opens the other opening. Thus by movement of the valves the respective ends of the cylinder 1 are alternately connected by passages 9 and 11, the chamber 13 and the pipe 17 with the vacuum line 33. Air inlet openings 39 are provided in the respective plugs 18 and 19, which openings are alternately closed by 110

the rod 16, which when so opened permit access of outer air at one side of the piston, the pressure of which moves the piston in the cylinder. The reduced end 16^b of the 5 rod operates to close or open the opening in the plug 18 and the reduced portion 16^a operating the same respecting the opening in the plug 19.

To operate the rod 16, I prefer to use an 10 electrical thermostat adapted to shift the current of a battery 40 or other electric circuit in the usual way, the circuit 35 being connected to the solenoid coil 23 and the contact 38, and the circuit 36 to the similar coil 24 15 and the contact 38^a, in which coils is a solenoid core 22 moved longitudinally by said coils when excited by the current. To this core is connected a rod 21 on which are collars 25 and 26 spaced apart and alternately 20 engaging an arm 20 fixed on the end of the rod 16 whereby as the core 22 moves in alternate directions, the collars will strike the arm and thus move the rod 16 to alternately shift the valves 14 and 15.

25 It will be noted that the valves move but a short distance compared with the distance between the collars 25 and 26, whereby the core operates as a hammer, and thus insures quick and certain movement of these 30 valves when a circuit is closed. When the core has moved and shifted the valves, it is desirable to break the circuit to save the battery. For this purpose I provide on the rod 16 near its outer end two insulators 27 spaced 35 apart by a conductor 28. The circuit 36 for the coil 24 is connected to insulated electrodes 29, which alternately engage the inner insulator 27 and the conductor 28, being shifted from one to the other as the rod 16 40 moves. The circuit 35 for the coil 23 is connected to similar insulated electrodes 30, which alternately engage the conductor 28 and the outer insulator 27 as the rod 16 is shifted. By this arrangement, whenever 45 the circuit 36 is closed by the thermostat, the parts being in position as shown in Fig. 2, the coil 24 will be excited and moving the core 22 within its sleeve will shift the rod 16 in the same direction and thus move the 50 electrodes 29 off the conductor 28 upon the inner insulator 27 and break the circuit. At the same time the opposing circuit 25 will be closed by the contact of the electrodes 30 with the conductor 28. If now by a change 55 of temperature, the movable electrode 37 of the thermostat should shift to the circuit 35, the reverse movement of the core shifts the valves and opens that circuit. At each shift of the valves 14 and 15 as thus described, the vacuum line would be alternately connected with the respective ends of the cylinder 1 and the opposite end of the cylinder opened to the outer air and thus the valve 4 would be alternately opened and 60 closed to regulate the flow of steam or water 65

to the radiator to maintain constant temperature in the apartment containing the thermostat.

What I claim is:

1. The combination with a heating system 70 including a valve device having an extending valve stem, of a cylinder, a piston operating in the cylinder and connected to said valve stem, a casing having transverse partitions spaced apart and with alined apertures having valve seats and forming a plurality of chambers with the chambers communicating respectively with the cylinder at opposite sides of the piston and with air vents leading therefrom, a pipe between the 80 intermediate chamber and the vacuum line of said system, a rod extending through said casing and its partitions and intersecting said air vents and adapted to close the same when disposed in one position, valves carried by 85 said rods and adapted to be alternately seated upon the seats of said apertures, a thermostat, and an electrical means between said thermostat and rod whereby the movements of said rod is controlled by 90 the operation of said thermostat by the influence of change in the temperature.

2. The combination with a heating system including a valve device having an extended valve stem, a cylinder, a piston operating in the cylinder and connected to said valve stem, a casing having transverse partitions spaced apart and with alined apertures having valve seats and provided with a plurality of chambers with the end chamber connecting with the cylinder at opposite sides of said piston and with air vents leading therefrom, a pipe between the intermediate chamber and the vacuum line of said 100 system, a rod extending through said casing 105 and its partitions and intersecting said air vents and adapted to close the same when disposed in one position, valves carried by said rod and adapted to be alternately seated upon the seats of said apertures, a thermostat, a solenoid having two independent coils and connected respectively to the opposite poles of said thermostat, and means whereby the operation of the core of said 110 solenoid actuates said rod.

3. The combination with a heating system including a valve having an extended valve stem, a cylinder, a piston operating in the cylinder and connected to said valve stem, a casing having transverse partitions 120 spaced apart and with alined apertures having valve seats and providing a plurality of chambers with the end chambers communicating with the cylinder at opposite sides of said piston and with air vents leading therefrom, a pipe between the intermediate chamber and the vacuum line of said system, a rod extending through said casing and its partitions and intersecting said air vents and adapted to close the same when disposed in 125 130

one position, valves carried by said rod and adapted to alternately seat upon the seats of said apertures, a thermostat, a solenoid having two independent coils connected respectively to the opposite poles of said thermostat, and with stops spaced apart a greater distance than the stroke of said valved rod, and an arm extending from said rod into the paths of said stops, whereby said rod is 10 forcibly actuated by the movement of said core.

4. The combination with a heating system including a valve device having an extended valve stem, a cylinder, a piston operating in the cylinder and connected to said valve stem, a casing having transverse partitions spaced apart and with alined apertures having valve seats and providing a plurality of chambers with the end chambers connecting 15 with the cylinder at opposite sides of said piston and with air vents leading therefrom, a pipe between the intermediate chamber and the vacuum line of said system, a rod extending through said casing and its partitions and intersecting said air vent and adapted to close the same when disposed in one position, valves carried by said rod and adapted to be alternately seated upon the seats of said apertures, a thermostat, a solenoid 20 having two independent coils and connected respectively to the opposite poles of said thermostat, means whereby the operation of the core of said solenoid actuates said rod, and a circuit breaker arranged in the 25 circuit of said thermostat.

5. The combination with a heating system including a valve having an extended valve stem, a cylinder, a piston operating in the cylinder and connected to said valve stem, 40 said valve stem having a passage connecting the inlet side of the valve with the upper part of said cylinder, a second cylinder, a piston in the second cylinder and connected to said valve stem, a casing having 45 transverse partitions spaced apart and with alining apertures having valve seats and providing a plurality of chambers with the end chamber communicating with the second mentioned cylinder at opposite sides 50 of the second mentioned piston and with air vents leading therefrom, a pipe between the intermediate chamber and the vacuum line of the system, a rod extending through said casing and its partitions and intersecting 55 said air vents and adapted to close the same when disposed in one position, valves carried by said rod and adapted to alternately seat upon the seats of said apertures, a thermostat, a solenoid having two inde- 60 pendent coils connected respectively to the opposite poles of said thermostat, said solenoid including a core and stops, said stops spaced apart a greater distance than the stroke of said valve rod, and an arm extending from said rod into the path of said stops, whereby said rod is 65 forcibly actuated by the movement of said core.

stops, whereby said rod is forcibly actuated by the movement of said core.

6. The combination with a heating system including a valve and an extended valve stem, a cylinder, a piston operating in the cylinder and connected to said valve stem, a casing having a plurality of communicating chambers, the communication between the chambers being arranged in alinement and having valve seats, a pipe between one 75 of the chambers and the vacuum line of the system, a rod in said casing extending through the communications of the chambers of the casing, valves carried by said rod and adapted to alternately seat upon 80 the seats of said communication between the chambers, a thermostat, a solenoid having two independent coils connected respectively to the opposite poles of said thermostat, said solenoid including a core and 85 stops, said stops being spaced apart a greater distance than the stroke of said valve rod, and an arm extending from said rod into the path of said stops whereby said rod is actuated by the movement of 90 said core.

7. The combination with a heating system including a valve having a valve stem, a cylinder, a piston operating in the cylinder and connected to said valve stem, a casing 95 having transverse partitions spaced apart, said partitions having alining apertures formed to provide valve seats, one of said chambers of the casing communicating with the cylinder at opposite sides of said piston 100 and having air vents leading therefrom, a connection between one of the chambers and the vacuum line of said system, a rod extending through the casing and its partitions and intersecting said air vents and 105 adapted to close the same when disposed in one position, valves carried by said rod and adapted to alternately seat upon said valve seats, a thermostat, a solenoid having two independent coils connected respectively to 110 the opposite poles of said thermostat, said solenoid including a core and a pair of spaced stops, and an arm extending from said rod into the path of said stops, whereby said rod is forcibly actuated by the movement of 115 said core.

8. The combination with a heating system including a valve having a stem, a cylinder, a piston operating in the cylinder and connected to said valve stem, a casing having a 120 series of communicating chambers, the communicating passages between the chambers being formed to provide valve seats, the end chambers communicating with the cylinder at opposite sides of said piston, the cylinder having air vents leading therefrom, a rod extending through said casing and its partitions and intersecting said air vents to close the same when the rod is disposed in one position, valves carried by said rod and 125

adapted to alternately seat upon said valve seats, a thermostat, a solenoid having two coils connected respectively to opposite poles of said thermostat, a single core common to both of said coils, and means whereby the alternate movements of said core under the influence of said coils actuates the controlling valve.

9. The combination with a heating system
10 including a valve having a valve stem, a cylinder, a piston operating in the cylinder and connected to said valve stem, a casing having a series of communicating chambers, the communications between the chambers
15 being formed to provide valve seats, a pipe between one of the chambers and the

vacuum line of the system, a rod extending through said casing, valves carried by said rod and adapted to alternately seat upon said valve seats, a thermostat, a solenoid 20 including a core, and means between the solenoid and said rod whereby the alternate movements of the core of the solenoid under the influence of said coils actuates the controlling valve, and a circuit breaker ar- 25 ranged in the circuit of said thermostat.

In testimony whereof I affix my signature in presence of two witnesses.

FRANK ARTHUR SIMONDS.
